UNITED STATES PATENT OFFICE

JULIUS HORWATH, OF CHICAGO, ILLINOIS, ASSIGNOR TO ARVEY CORPORATION, OF CHICAGO, ILLINOIS, A CORPORATION OF ILLINOIS

DISPLAY STAND FOR MERCHANDISE

Application filed November 23, 1929. Serial No. 409,266.

This invention relates to improvements in stands for displaying merchandise for sale and for similar purposes. The invention has reference particularly to a display stand 5 made of paper board or similar material, although it will presently appear that any suitable material may be used as desired.

In a co-pending application for Letters Patent of the United States, executed by me 10 of even date herewith, I have disclosed a construction of display stand which is so arranged that packing cases or shipping cases of packages of merchandise can be readily accommodated in the lower portion of the 15 stand, the top portion of the stand being arranged to receive some of these packages for display. The arrangement disclosed in that application is such that the top portion of the display stand, although made of such 20 material as paper board, is so reenforced that it is made very stiff and fully capable of supporting a considerable amount of weight. In the construction of that application also the upper portion of the display stand is intended 25 for connection to the lower section of the display stand in such a manner that when the parts are assembled they reenforce and compliment each other and their assembly together is in some respects a necessary incident 30 in order to produce the entire completed stand.

The present invention relates to a construction in which the upper portion of the display stand is protected or reenforced by side panels 35 which are integral with or constitute a definite portion of the upper portion of the display stand, in such a way that this upper portion of the stand becomes a completely self-sustaining and self-sufficient structure which 40 will maintain its shape and strength even when disconnected from the lower section upon which it may be mounted.

Another feature of the present invention relates to the provision of a top section which 45 may be set directly down upon the upper edge of a packing case or similar housing. In this way the packing case itself, within which the merchandise is shipped and delivered to the store, may be thereafter used as a lower or 50 base section of the display stand, the top sec-

tion being set in place thereon and supported thereby. Under this arrangement said top section cooperates to close the base section, and at the same time the base section serves to support the top section at the proper elevation. 55

Another feature of the invention relates to the provision of a knock-down construction of the top section, the same being of such arrangement that when knocked-down it can be folded up into a relatively thin package whose length and width are substantially the same as the size of one of the panels of the packing case itself. This will make it possible to ship the top section of the display 60 stand at the same time that the packing case is shipped and with little or no additional expense in the operation. 65

Other objects and uses of the invention will appear from a detailed description of the 70 same which consists in the features of construction and combinations of parts herein-after described and claimed.

In the drawings:

Figure 1 shows a perspective view of a display stand embodying the features of the present invention, the top section being shown as mounted upon and supported by the upper edge of a packing and shipping case which may contain packages of merchandise to be displayed; 75

Figure 2 shows a development of the back and side panels;

Figure 3 shows a development of the bottom panel;

Figure 4 shows a perspective view of the bottom panel partially folded up;

Figure 5 shows a view similar to that of Figure 1 with the exception that the top section is shown as being mounted upon a special 90 base section instead of the packing and shipping case;

Figure 6 shows a perspective view of the base section of Figure 5, with the top section and the reenforcing bar removed therefrom; 95

Figure 7 shows a perspective view of the top section of Figure 5 in partially folded condition; and

Figure 8 shows a perspective view of the re-enforcing bar partially folded together. 100

Referring first to the arrangement shown in Figures 1, 2, 3, and 4, in this case the display stand includes a top section 10 which is shown as being removably mounted upon 5 and supported by a base section 11. In the particular arrangement illustrated, this base section 11 comprises a packing and shipping case wherein packages of the merchandise may be contained and may be shipped and 10 delivered.

The top section 10 includes a member which establishes the back panel 12 and side panels 13 and 14. These panels are of suitable shape and finish to give a pleasing display of the 15 materials. There is a floor panel or member designated in its entirety by the numeral 15. The same includes a series of panels 16, 17, and 18, together with transverse reenforcing and supporting rib portions 19, 20, 21 and 20 22. These rib portions are formed as portions of the member 15 and they are established by properly folding the same as shown by the various fold lines indicated in the different figures. Each of the ribs 19, 20, and 25 21 is preferably of double thickness and therefore of double stiffness and strength. The rib 22 may be single as illustrated or it may also be of double strength.

The end portions of the ribs 19, 20, and 21 30 project beyond the edges of the panels 16 and 17. Preferably the panel 18 is tapered in width so that at its extreme front end it becomes of the same size as the rib 22.

The side panels 13 and 14 are slotted in their 35 lower portions as shown at 23, 24, and 25 to receive the projecting portions of the ribs 19, 20, and 21. The front edges of the panels 13 and 14 terminate slightly in advance of the openings 25 and consequently the tapering portion of the panel 18 is properly accommodated and taken care of as illustrated in 40 Figure 1.

The projecting portions of the ribs are 45 notched as shown at 26 in the different figures so that when the projecting portions have been extended through the openings 23, 24, and 25, said notches may be set down and engaged with the upper edge of the lower section 11, as clearly shown in Figure 1. 50 This being the case, the parts are all hooked together in such a manner that they can not become disconnected as long as the top section 10 remains on top of the packing case or base member 11.

The ribs 19, 20, 21 and 22 are of substantial 55 vertical dimension so that the section 15 is greatly reenforced in strength and is able to carry a very considerable load without buckling.

The construction shown in Figures 5, 6, 7, 60 and 8 is of slightly different arrangement in respect to details. In this case the top section 10 is similar in construction to that already explained.

65 However, the bottom section 15 is of some-

what different construction, and has its rear edge permanently attached to the lower edge of the back panel 12 as shown in Figure 7. For this purpose said section 15 has one-half 70 of its rear lug 19 permanently connected to the lower edge of the back panel 12, as by glue or otherwise, and during shipment the section 15 may be laid over flat against the back panel 12. When the device is to be assembled into working condition the member 15 is turned out into the position shown in Figure 7, the rear rib 19 is doubled up, and the other ribs are also doubled up and entered 75 into the proper openings of the side panels 13 and 14 respectively.

In connection with this operation it will be noted that the openings 23 of Figure 2 have been entirely cut out as shown in Figure 7, to establish the relatively large notches 28, such being necessary in order to permit the parts 80 to be properly manipulated due to the permanent attachment of the member 15 to the lower edge of the back panel 12.

In the construction of Figures 5, 6, 7 and 8, the base section is shown as comprising a special stand including the front panel 29 and the side panels 30 and 31. The projecting portions of the ribs 19, 20, 21, and 22 are hooked over the upper edges of this base member as clearly illustrated.

If desired also a reenforcing bar 32 may be extended across between the lower rear portions of the panels 30 and 31 as clearly shown in the different figures.

The arrangement as shown in Figures 5, 6, 7, and 8 is especially intended for use in those cases where the packing and shipping case may be unsightly or where it may be desired to display the material therefrom simultaneously on more than one stand.

While I have herein shown and described only certain embodiments of the features of my present invention, still I do not intend to limit myself thereto except as I may do so in the claims.

I claim:

1. As a new article of manufacture, a shelf member adapted for mounting and support upon the upper portion of a base member, said shelf member comprising a blank cut to establish a rear panel together with forwardly extending side panels, and a floor for said shelf member, said floor comprising a series of horizontal sections located in the same horizontal plane, which plane passes in proximity to the lower portions of the panels aforesaid, and including a series of ribs located intermediate between the consecutive edges of the floor sections and projecting beyond the edges of the side panels and adapted to rest on and be supported by the base member aforesaid, substantially as described.

2. As a new article of manufacture, a shelf member adapted for mounting and sup-

port upon the upper portion of a packing case or the like, said shelf member comprising a blank cut to establish a rear panel together with forwardly extending side panels, and a blank cut to establish a series of shelf panels together with intermediate rib portions located between the said shelf panels, said rib portions being centrally folded and having their upper edges folded at right angles to the adjacent shelf panels, whereby each rib portion is of double thickness and whereby the adjacent edges of the shelf panels are brought substantially into contact with each other with the shelf panels lying in the same horizontal plane, and a hinge connection between the rear portion of the shelf panel section and the lower portion of the rear panel, substantially as described.

3. As a new article of manufacture, a self contained shelf member adapted for mounting and support upon the upper portion of a base member, said shelf member comprising a blank cut to establish a rear panel together with forwardly extending side panels, a shelf panel member having a series of shelf panels together with intermediate rib portions, said rib portions being centrally folded and having their edges integral with the shelf panels and folded with respect thereto, whereby the shelf panels may lie in the same horizontal plane at right angles to the back panel, a hinge connection between the rear edge of the shelf panel section and the lower portion of the back panel above the lower edge thereof, the rib portions projecting beyond the shelf panels, and suitable openings in the forwardly extending side panels to receive said projecting rib portions, substantially as described.

JULIUS HORWATH.
